UNITED STATES PATENT OFFICE

LEONARD DAY, OF BRONX, NEW YORK, ASSIGNOR TO LINCOLN BUILDERS SUPPLY CO., INC., OF BROOKLYN, NEW YORK

DESIGN FOR A DOOR PEEPHOLE FRAME

Application filed November 1, 1928. Serial No. 28,722. Term of patent 3½ years.

To all whom it may concern:

Be it known that I, LEONARD DAY, a citizen of the United States, residing in the borough of Bronx, county of Bronx, city and State of New York, have invented a new, original, and ornamental Design for a Door Peephole Frame, of which the following is a specification, reference being had to the accompany-

ing drawing, which forms a part of this application.

In the drawing, the single figure is a partly inclined front view, showing my design.

I claim:—

The ornamental design for a door peephole frame, as shown.

LEONARD DAY.
